UNITED STATES PATENT OFFICE.

AUSTIN F. JACKSON, OF TAUNTON, MASSACHUSETTS.

DESIGN FOR A SPOON.

SPECIFICATION forming part of Design No. 21,136, dated October 27, 1891.

Application filed September 22, 1891. Serial No. 406,534. Term of patent 7 years.

To all whom it may concern:

Be it known that I, AUSTIN F. JACKSON, a citizen of the United States, residing at Taunton, in the county of Bristol and State of Massachusetts, have invented and produced a new and original Design for Handles of Spoons, Knives, Forks, &c., of which the following is a specification, reference being had to the accompanying drawing, forming part thereof.

10 The figure is an upper or face view of my design applied to a coffee-spoon.

The leading feature of my design is the representation of a daisy-blossom *a* applied to the end of the handle of the spoon. Just below the blossom is a bud *b* and leaves *c* of the daisy extending from the shank of the spoon outwardly toward its end. The daisy-

blossom and the bud and leaves form with their outer edges the margin of the handle and impart their contour to the same.

What I claim is—

The design for the handles of spoons, knives, forks, &c., consisting of the representation of a daisy-blossom *a*, forming the end of the handle, with bud and leaves *b* *c* reaching downwardly therefrom, the said features forming with their outer edges the margin of the handle and imparting their contour to the same, substantially as shown and described.

AUSTIN F. JACKSON.
